ARMCHAIR

Alberto Rosselli, Milan, Italy, assignor to Industria Arredamenti Fratelli Saporiti, Besnate, Varese, Italy

Filed May 28, 1971, Ser. No. 148,303

Term of patent 7 years

Int. Cl. D6—01

U.S. Cl. D6—71

FIG. 1

FIG. 1 is a front view of an armchair embodying my new design;

FIG. 2 is a side view of the armchair; and

FIG. 3 is a rear view thereof.

The opposite side of the armchair, not shown in the drawing, is the mirror image of the one seen in FIG. 2.

I claim:

The ornamental design for an armchair, as shown and described.
